DESIGN FOR A TOY GUN

Harry Reom, Jr., Oakland, Calif.

Application May 19, 1936, Serial No. 62,722

Term of patent 3½ years

To all whom it may concern:

Be it known that I, Harry Reom, Jr., a citizen of the United States and a resident of Oakland, in the county of Alameda and State of California, have invented a new, original, and ornamental Design for a Toy Gun, of which the following is a specification, reference being had to the accompanying drawing, forming part thereof, wherein

I claim:
The ornamental design for a toy gun substantially as shown.

HARRY REOM, JR.
